UNITED STATES PATENT OFFICE.

ELI J. GAGNON, OF EXETER, NEW HAMPSHIRE.

PAIL-TURNING MACHINE.

Application filed July 15, 1921. Serial No. 485,054.

To all whom it may concern:

Be it known that I, ELI J. GAGNON, a citizen of the United States, residing at Exeter, county of Rockingham, State of New Hampshire, have invented certain new and useful Improvements in Pail-Turning Machines, of which the following is a specification.

In my present invention the subject matter immediately involved is a machine especially adapted for the making of wooden pails, and although it is adaptable to other uses, the embodiment shown is primarily intended for this special purpose and I shall therefore treat my invention from that point of view.

In work of this sort the principal operations are the trimming and sanding. The difficulties in performing such operations rapidly and in an organized machine are increased by the very nature of the work as it involves the handling of assembled staves which must be held so that they can be readily worked upon and which must be hooped without breaking the original assembly so that there can be no chance of losing the finish which has been given to them in their assembled condition.

I accomplish these results by certain features and combinations which I have embodied in an organized machine illustrated in the accompanying drawings as a specific embodiment adapted to the manufacture of pails along the usual lines of such manufacture. Throughout the specification and drawings like reference characters are employed to indicate corresponding parts, and in the drawings:

Fig. 1 is a front elevation of the upper portion of a machine in accordance with my invention.

Fig. 2 is a view from the opposite side, partly in section to show the controls.

Fig. 3 is a plan view of the machine.

Figs. 4 and 5 are partial sections on approximately the line 5—5, Fig. 3, and showing the latching mechanism for the intermittently rotatable work carrying head in its disengaged and engaged positions, respectively.

Figs. 6 and 7 are detail views of the spindle drives and the controls.

Fig. 8 is a diagrammatic view of the stop control.

Figs. 9 and 10 are details of the gearing and control for the spindle head.

Fig. 11 is a detail view illustrating the action of the permanent hoop setting roller, and

Figs. 11^a to 15 are diagrammatic views 60 showing the working phases of the machine in its successive operations, Fig. 14^b representing the finished pail staves hooped up as delivered from the machine.

The machine shown in these drawings 65 comprises a supporting base 1 on which is carried a frame 2 above which is a super-structure 3. In the frame 2 is journaled a main shaft 4 driven by a pulley 5 from any suitable source of power. In the super- 70 structure 3 is journaled a shaft 6 on which is mounted a rotary head 10 carrying the work spindles 11. The head 10 is provided with an external gear 10¹ which meshes with a pinion 13 on a shaft 14 carrying a pulley 75 15 which is belted to the pulley 16 on the main shaft 4 so that the head 10 can be turned to bring the spindles 11 from station to station for their successive operations.

These stations, as will be seen by reference to Figs. 11^a to 15, are first the assembling station A, at which the rough staves which have been assembled and held temporarily by a heavy iron hoop are clamped on the spindle; the planing station B at 80 which the staves are trimmed by a rotary cutter 23, and the sanding station C at which the trimmed staves are finished by a sanding drum 32. Upon return to the station A the finished staves are hooped and 85 removed and a new rough stave assembly applied and the temporary holding ring knocked off. The details of this operation will be further described later.

At the planing station B, which is at the 90 top of the machine, as is best shown in Figs. 3 and 4, I provide a cutter shaft 20. Fastened on said shaft adjacent either end thereof is a pulley 21^a which is cross-belted as indicated at 21^b to a pair of pulleys 21 100 fastened on the ends of a counter shaft 21^c. One of the pulleys 21 is belted as indicated at 21^d to a driving pulley 22 on the main drive shaft. On the shaft 20 is a cutter 23. The shaft 20 is journaled in a head 24 vertically adjustable by screws 25 carrying sprockets 26 connected by a chain 27 and operated by a handle 28 for giving the proper adjustment relative to the work on the spindles 11.

At the sanding station C I provide a shaft 30 which is journaled in a cradle 33 ad-

justably mounted as at 34 in the top of the frame 2. The shaft 30 is provided with a universal joint 21' (Fig. 3) and has a fixed bearing 35 on the frame of the machine. The 5 jointed form of shaft allows the sanding drum 32, which is fast on said shaft, to be moved closer to the work when a small-sized pail is being operated upon.

The head 10 which is covered by a guard 10² is locked at each step of its intermittent rotation from station to station by a latch 40 pivoted to the frame at 41 and operated by a rod 42 which passes through the hollow shaft 14 which is the clutch shaft of the 15 machine, and as previously described carries the pinion 13 by which the head 10 is intermittently rotated.

The shaft 14 has at its outer end the cone member 43 of a cone clutch which engages 20 with the opposite member of the clutch in the pulley 15. The pulley 15 is continuously driven from the pulley 16 and in turn drives a pulley 50 on a shaft 51 which carries a pinion 52 meshing with the reduced concentric portion 110^a of a double gear 110', Fig. 25 6. This gear is free to turn on shaft 6 and the main gear portion thereof meshes with a surrounding gear train 110 which drives the three work spindles 11 of the head 10.

30 The clutch member 43 is operated by a lever 44 fulcrumed at 45 in a bracket 46. This lever is operated by a link 47 connecting a pair of toggles 48 which are operated by the rod 49 and treadle 49¹. The rod 49 has its 35 upper end adjacent the path of a cam member 60. The cam member 60 is mounted on the shaft 14 and rotates with it making three revolutions to each turn of the head 10 so as to stop the spindles 11 at each of the three 40 stations A, B and C.

The mechanism at station A comprises devices for pushing on the hoop after the assembled staves have been planed and sanded. The finished work is then removed and 45 a new assembly of rough staves is slipped on the spindle 11 and held between two opposed clamping pieces 61 and 62. The clamping piece 62 is adjustable and removable by a nut 63, this nut being engageable 50 by a wrench head 64 on a shaft 65 driven by a pulley 66 which is belted to a pulley 67 on the main shaft 4. The reverse motion is given the shaft 65 by a pulley 68 driven from a pulley 69 by a crossed belt. The 55 belts are operated by a pair of belt tighteners. The tightener for the straight belt is indicated at 70 (see Fig. 2) and the tightener for the cross belt at 71. The tightener 71 is on a rock shaft 73 operated by a link 74 and a treadle 75 but the tightener 70 is 60 on a shaft 76 operated by a link 77 from a treadle 78.

The shaft 65 is splined to the pulleys supported in bearings 80 mounted on a bracket 81 at the side of the machine. The shaft

also has a bearing 82. The bearing 82 is 70 slidable in a groove formed in the base of the same casting which carries the bearings 80 by means of a hand lever 83 pivoted to the frame 2. When the lever 83 is swung in one direction, the bearing 82, and with it the shaft 65 is moved inwardly to engage the wrench head 64 of said shaft with the nut 63 on the clamping piece 62 (see Fig. 5). When the lever 83 is swung in the opposite direction, the parts 64 and 63 are disengaged (see Fig. 4).

75 Supported on a bracket 90 which is mounted on the bearing 82 is a swinging arm 91 having on its end a roller 92 which is adapted to be swung up against a permanent hoop H when it is applied to the staves prior to their removal from the clamps.

80 The operation of the machine is as follows: Referring to Figs. 11^a to 15, it will be seen as indicated in Fig. 11^a, that after an assembly of rough pail staves have been put on and clamped at station A and moved to station B the cutter 23 will be trimming the staves at that station while another set of staves is put on at station A (see Fig. 12). In Fig. 13 I have indicated the sanding drum 32 at station C at work on the planed staves which have come from station B. During this operation at station C while the sanding drum is finishing the staves, the cutter 23 is trimming the staves previously put on at A, and at the same time a new set of staves is being clamped at A. In Fig. 14, I have indicated how the staves previously sanded, as shown in Fig. 12, at C have moved again to station A. At the same time the next set of staves has moved from the cutter at B and is being sanded by the drum 32. At this point in the operation the permanent hoop H is to be applied to the staves at station A. This I have indicated diagrammatically in Fig. 14, showing the roller 92 pushing on the permanent hoop H while the spindle is rotating.

105 At this stage, the revolution of the head 10 is automatically stopped and the head is locked with one of its spindles 11 in alignment with the station A. This is accomplished as follows:

110 The cam 60 rotating with the shaft 14 and making three revolutions to each complete revolution of the head 10 contacts the rod 49 and through the connections 48, 47, 44 and 42 moves the cone member 43 of the clutch out of engagement with the cooperating clutch member, thereby disconnecting the shaft 14. The same movement of the cone member 43 and rod 42 causes the latch 40 which is actuated from said rod 42 to engage in one of the locking notches 10^a of the head, thereby automatically locking the head against revolution with one of the spindles 11 in alignment with the station A.

115 Just before the revolution of the head 10

is stopped, the rounded head 11' of the spindle 11 which is approaching alinement with the station A is brought against a fixed cam 100 mounted on the super structure 3 of the machine, and said spindle is thereby moved longitudinally a distance sufficient to carry its gear 110 out of mesh with the other gears of the gear train, which is driven from the pinion 52 (see Fig. 7) and 10 into mesh with a locking gear 101 which is mounted on a shaft 101' fixed in a bracket 101² carried by the superstructure 3. The endwise movement of the spindle is opposed by a coiled spring 11² which is confined 15 about the spindle between the rounded head 11' thereof and the revolute head 10. The spring 11² thus serves to return the spindle 11 to its normal position indicated in Figs. 6 and 9 when the revolute head 10 is again 20 released and commences its intermittent revolution thereby carrying the rounded head 11' of the spindle which has just been disconnected out of the influence of the cam 100. When the spindle is in alinement with 25 station A is disconnected, as shown in Figs. 7 and 10, the gear 101 holds said spindle against rotation by engagement with the gear 110 of the spindle drive gear train. This holds the spindle which is at station 30 A and which has now had its hoop applied, against rotation. The wrench head 64 is then moved up to engage the nut 63 and the cross belt drive started by the treadle 75 to back off the nut. The clamp 62 is then 35 disengaged and taken off and the hooped staves removed and a new assembly of staves set between the clamps, whereupon the shaft 65 is reversed by the straight belt put in operation by the treadle 78 and the 40 wrench head 64 brought up and the nut brought back on the spindle clamping the staves in position and ready to be moved at the next operation of the machine to station B. The machine is again started by 45 depressing the treadle 49¹ and the head 10 given its partial rotation to bring the new staves to station B.

From the foregoing it will be seen that the attention of the operative is only required at station A in the hooping and removing of finished staves and the clamping of an assembly of unfinished staves on the spindle.

In this manner with my machine staves 55 are not only planed and sanded but are hooped ready to go on to the next step in the manufacture.

Various modifications in the structure and detail of combination may be made all 60 without departing from the spirit of my invention if within the limits of the appended claims.

What I therefore claim and desire to secure by Letters Patent is:

1. In a pail finishing machine, a rotatable 65 head, a plurality of rotatable clamps for a stave assembly spaced about the same, a plurality of operating stations disposed adjacent the orbital path of the stave clamps and operatively disposed in the path of 70 peripheral movement of the stave assembly when rotated, one of said stations comprising a hoop setter and a rotatable wrench axially movable relative to said clamp for 75 releasing the stave clamp, means for rotating the head and means for locking the head at each stage of its movement and stopping said head rotating means.

2. In a pail finishing machine, a rotatable 80 head, a plurality of rotatable spindles, clamping members on said spindles for holding a stave assembly, one of said members having a threaded engagement with said spindle, a plurality of operating stations disposed adjacent the orbital path of said 85 spindles and operatively disposed in the path of peripheral movement of a stave assembly when rotated on said spindles, one of said stations having a rotatable wrench shaft reciprocable in axial alignment with 90 the spindle position at said station, means for selectively rotating said wrench shaft in opposite directions, and means for reciprocating said wrench shaft to engage the said 95 threaded clamp member.

3. In a pail finishing machine, a rotatable 100 head, a plurality of rotatable spindles, clamping members on said spindles for holding a stave assembly, one of said members having a threaded engagement with said spindle, a plurality of operating stations disposed adjacent the orbital path of 105 said spindles and operatively disposed in the path of peripheral movement of a stave assembly when rotated on said spindles, one of said stations having a rotatable wrench shaft reciprocable in axial alignment with the spindle position at said station, means for selectively rotating said 110 wrench shaft in opposite directions, and means for reciprocating said wrench shaft to engage the said threaded clamp member, and a hoop setter adjustably mounted in relation to said spindle position and having a hoop engaging roller, and means for moving said roller against a hoop to force the same in position upon rotation of the spindle.

4. In a pail finishing machine, a rotatable 120 spindle, a threaded clamping member on said spindle, a rotatable wrench shaft reciprocable in axial alignment with the spindle, means for selectively rotating said wrench shaft in opposite directions, and means for reciprocating said wrench shaft to engage 125 said threaded clamp member, and a hoop setter adjustably mounted in relation to said spindle position and having a hoop engag-

- ing roller, and means for moving said roller against a hoop to force the same in position upon rotation of the spindle.
5. In a pail finishing machine, a rotatable head, a plurality of rotatable spindles, clamping members on said spindles for holding a stave assembly, one of said members including a threaded nut portion, a plurality of operating stations disposed adjacent the orbital path of said spindles and operatively disposed in the path of peripheral movement of the stave assembly when rotated on said spindles, one of said stations having a hoop setter adjustably mounted in relation to said spindle position and having a hoop engaging roller, and means for moving said roller against a hoop to force the same in position upon rotation of the spindle.
- 20 6. In a pail finishing machine, a revoluble and rotatable spindle, a drive therefor, a loading and unloading station past which said spindle moves, means for stopping the spindle at said station, a work clamp movable on said spindle, a power wrench movable into and out of effective engagement with said clamp when said spindle is stopped, and a drive operated from said spindle drive for selectively rotating said wrench in opposite directions to advance or retract said clamp along said spindle.
- 25 7. In a pail finishing machine, a revoluble and rotatable spindle, a drive therefor, a loading and unloading station past which said spindle moves, means for stopping the spindle at said station, a work clamp movable on said spindle, a power wrench movable into and out of effective engagement with said clamp when said spindle is stopped, a drive operated from said spindle drive for selectively rotating said wrench in opposite directions to advance or retract said clamp along said spindle, a hoop setter at said loading and unloading station, and means operable when the spindle is stopped to move said hoop setter against a hoop and force the hoop into position for location about the stave assembly when the spindle again commences to rotate.
- 30 45 8. In a pail finishing machine, an intermittently revoluble head, a plurality of work spindles rotatable thereon, a plurality of operating stations disposed adjacent the orbital path of said spindles including a station at which the spindles are loaded and unloaded, means for stopping and locking the head and for stopping the rotation of the spindle opposite said station, a work clamp movable on each spindle, a power wrench movable into and out of engagement with the work clamp of the spindle which has been stopped opposite the loading and unloading station, and means for selectively rotating said wrench in opposite directions to advance or retract the work clamp along said spindle.
- 35 9. In a pail finishing machine, an intermittently revoluble head, a drive therefor, a plurality of work spindles rotatable upon said head, a plurality of operating stations disposed adjacent the orbital path of said spindles including a station at which the spindles are loaded and unloaded, means for stopping and locking the head and for stopping the rotation of the spindle opposite said station, a work clamp movable on each spindle, a power wrench driven from the drive for the revoluble head and selectively rotatable in opposite directions to advance or retract the work clamp along the spindle which has been stopped opposite the loading and unloading station to apply and remove the work clamp, means for moving said wrench into and out of engagement with said clamp, a hoop setter at said loading and unloading station, and means operable when the spindle is stopped to move said hoop setter against a hoop and force the hoop into position for location about the stave assembly when the spindle again commences to rotate.
- 40 45 50 55 60 65 70 75 80 85 90 95

In testimony whereof I affix my signature in presence of two witnesses.
